UNITED STATES PATENT OFFICE

165,996

ANALYTICAL BALANCE

Carl Otto and Jay Doblin, New York, N. Y., as-
signors to The Torsion Balance Company, Clif-
ton, N. J., a corporation of New York

Application April 3, 1951, Serial No. 14,701

Term of patent 14 years

(Cl. D52—10).

To all whom it may concern:

Be it known that we, Carl Otto and Jay Doblin, both citizens of the United States of America, both residing in the Borough of Manhattan, city, county, and State of New York, have invented a new, original, and ornamental Design for an Analytical Balance, of which the following is a specification, reference being had to the accompanying drawings forming part thereof, wherein:

Figure 1 is a front elevational view of an analytical balance showing our new design.

Fig. 2 is a top plan view of Fig. 1.

Fig. 3 is a side elevation as viewed from the right hand side of Fig. 1.

The characteristic features of the design reside in the solid line portions.

We claim:

The ornamental design for an analytical bal-
ance, as shown and described.

CARL OTTO.
JAY DOBLIN.
